* cited by examiner

Primary Examiner—Louis S. Zarfas*Assistant Examiner*—John Windmuller(74) Attorney, Agent, or Firm—Drinker Biddle & Reath LLP(57) CLAIM

The ornamental design for a clip, as shown and described.

DESCRIPTION

FIG. 1 is a front elevational view of a clip showing my new design;

FIG. 2 is a rear elevational view of the clip of FIG. 1;
 FIG. 3 is a left side view of the clip of FIG. 1, the right side view being a mirror image.FIG. 4 is a top plan view of the clip of FIG. 1; and,
 FIG. 5 is a bottom plan view of the clip of FIG. 1.
